(57) CLAIM

I claim the ornamental design for a bra, as shown and described.

DESCRIPTION

FIG. 1 is a left, front perspective view of a bra, showing my new design;

FIG. 2 is a front view thereof;

FIG. 3 is a right, front perspective view thereof; and,

FIG. 4 is an enlarged view of the selected region of FIG. 1. The dot-dash broken line rectangles depict the limits of the enlarged view and form no part of the claimed design. The dot-dash broken lines within the broken line rectangles represent boundaries of the claimed design and form no part thereof. The regular broken lines depicting the remainder of the bra show features that form no part of the claimed design.
